[57] CLAIM

The ornamental design for a combined container/bottle and cosmetic wand applicators, or the like, as shown and described.

DESCRIPTION

FIG. 1 is a side elevational view with partial cross-section of a combined container/bottle and cosmetic wand applicators or the like showing our new design;

FIG. 2 is a side elevational view, without cross-section showing our new design;

FIG. 3 is a front elevational view, the rear being the same;

FIG. 4 is an exploded rear elevational view showing a second embodiment of our new design wherein the caps are modified;

FIG. 5 is a top plan view thereof with caps removed;

FIG. 6 is a bottom plan view with cap removed;

FIG. 7 is a side elevational view with partial cross-section showing a third embodiment of our new design;

FIG. 8 is a side elevational view thereof without cross-section;

FIG. 9 is a front elevational view thereof;

FIG. 10 is an exploded rear elevational view showing a fourth embodiment of our new design with modified caps;

FIG. 11 is a top plan view thereof with caps removed; and

FIG. 12 is a bottom plan view thereof with cap removed.
